CROSS-TIE AND RAIL-CLAMP THEREFOR.

1,322,781.

Specification of Letters Patent.

Patented Nov. 25, 1919.

Application filed July 3, 1919. Serial No. 308,609.

To all whom it may concern:

Be it known that I, GEORGE E. FREY, a citizen of the United States of America, and resident of Steubenville, county of Jefferson, and State of Ohio, have invented 5 certain new and useful Improvements in Cross-Ties and Rail-Clamps Therefor, of which the following is a specification.

This invention relates to certain improvements in railway crossties and rail clamps, and it has for its primary object to provide 10 a metallic crosstie and chair structure having improved means for securing rails thereon.

15 In describing the invention in detail, reference is herein had to the accompanying drawings, in which—

Figure 1 is a top plan view of the invention, showing track rails mounted in place;

20 Fig. 2 is a view of the same partly in side elevation and partly in section;

Fig. 3 is a section on line 3—3, Fig. 2, with the rail and rail clamp removed;

25 Fig. 4 is a similar section, enlarged, showing the rail and clamp in place;

Fig. 5 is a section on line 5—5, Fig. 4, showing the lugs of the chair in upright position; and

Fig. 6 is a side elevation of a modified 30 form of clamp.

Referring to said drawings, in which like designating characters distinguish like parts throughout the several views—

1 indicates a metallic crosstie which is 35 herein illustrated as being of semi-cylindrical form, but which may, if preferred, be of other trough-like form. Mounted upon said crosstie at appropriate points are two chairs adapted for the reception of the 40 track rails 2, each of said chairs being composed of a single piece of material and comprising a horizontal base or seat 3 upon which the rail is mounted. Said seat is disposed transversely with respect to the tie 45 and has its opposite ends turned downward to form attaching members 4 which are bolted or riveted to the sides of the tie, as shown. At each side of said seat are two integral upright tongues 5 which may be 50 of short length, as shown in Figs. 1, 2 and 3, for engaging the opposite lateral edges of the base of the rail 2, or which may be made of a greater length, as shown in Figs. 4 and 5, so that they are adapted to be bent

over into overlying clamping relation to 55 said rail base, as shown in Fig. 4.

Located at each side of the seat 3 intermediate the tongues 5, which latter are spaced relatively, is an integral vertically-dependent apron-like abutment 6 which has 60 therein a hole or opening 7, preferably of rectangular form, of which the upper defining edge is located in approximately the plane of the under side of the seat 3. The openings in the opposite abutments are de- 65 signed to receive therein the correspondingly shaped shank of a clamp member 8 which has one end bent to form a hook 9 for seating upon the top of one side of the base of the rail 2, and which has its shank 70 underlying the seat 3 with its end projecting through and beyond the opposite abutment 6.

A second clamp member 10 designed to coöperate with said member 8 has a vertically disposed body adapted for adjustment along the projecting end of the shank of said member 8, a hole 11 being provided in said body in which said end of the member 8 is received. The upper end of said member 10 is turned inward and is adapted to assume overlying clamping relation to the adjacent side of the rail base. Provided in the projecting end of the shank of said member 8 is a vertically disposed slot 12 80 adapted for the reception of a wedge 13 in abutting relation to the outer face of the vertical body of the member 10, whereby said clamp members 8 and 10 are actuated relatively into close-gripping or clamping 85 relation to the opposite sides of the rail base. The abutment 6 on the side adjacent to the clamp member 10 is adapted to receive the body of said member thereagainst and prevents said member from being 90 swung by the wedge into a position wherein its body is inclined inwardly. While the opposite abutment may be omitted, it is preferred that such abutment be employed for rendering the chair reversible. 100

In the modified form of clamp illustrated in Fig. 6, the end of the shank of clamp member 8^a is reduced and screw threaded, as shown at 14, for the reception of a nut 15 by which the clamp members are relatively adjusted and secured. 105

What is claimed is—
The combination with a crosstie of

trough-like form, of a horizontal rail seat mounted on said crosstie, upright lateral tongues formed on said seat, a depending apron-like abutment formed at one side of said seat intermediate said tongues, said abutment having therein an opening of which the upper edge is located approximately in the plane of the under face of said seat, a clamp member comprising a hook for overlying a rail base at the side opposite said abutment and a shank underlying said seat and having its end projecting through the opening in said abutment, a second clamp member comprising an upright body adapted to seat against said abutment and having its upper end turned

inward for overlying the adjacent side of the rail base, said second member having therein a hole through which the end of said shank projects, and means acting 20 against said second member for exerting a drawing force whereby said members are relatively adjusted and are secured in adjusted position.

In testimony whereof, I affix my signature in presence of two subscribing witnesses.

GEORGE E. FREY.
